ATION OF PENNSYLVANIA.

PATTERN AND MEASURING MECHANISM FOR KNITTING-MACHINES.

1,203,087.

Specification of Letters Patent. Patented Oct. 31, 1916.

Application filed June 10, 1915. Serial No. 33,306.

To all whom it may concern:

Be it known that we, FRANK B. WILDMAN, a citizen of the United States, and GEORGE L. BALLARD, a subject of the King of Great Britain, residing at Norristown, Pennsylvania, have invented certain new and useful Improvements in Pattern and Measuring Mechanism for Knitting-Machines, of which the following is a specification.

One object of our invention is to provide a measuring means for the pattern mechanism of knitting machines which shall measure by the actual length of the fabric. Means directed to this end have been employed heretofore, and we would mention in this connection the toothed fabric roller as shown as an example in Letters Patent of the United States granted to us June 24, 1913, #1,065,487, at 19, operated by direct engagement with the fabric and connected to the measuring wheel or ratchet 8 to drive the same. While measuring mechanism operated by this card roller engaging the fabric produces good results and has met with favor by users of machines equipped therewith, there is a lack of accuracy and certainty in the use of the card roller owing to the variations in the tension of the fabric with which the card roller engages on its way to the take-up from the knitting head.

In carrying out our invention we discard the use of the fabric roller and secure an initial drive for our measuring means from means moving in consonance with the rotation of the take-up rolls. As is well understood by those skilled in the art, each time the take-up rolls make one revolution a definite and unvarying length of fabric has passed between said rolls, and by driving the measuring mechanism in exact accord with the take-up rolls it will be seen that for each revolution of the take-up roll or part thereof we get a definite and unvarying length or degree of movement of our measuring member, and if this is in the form of a wheel each revolution of said take-up rolls will cause a rotation of the measuring wheel through a certain definite angle, and accurate measurement according to the length of fabric is thus secured.

Broadly speaking, it is not new to operate pattern mechanism in consonance with the

rotation of the take-up rolls, as such mechanism is disclosed in Letters Patent of the United States granted to F. B. Wildman, 642,402, and 642,403, January 30, 1900. Our present invention is an improvement on the pattern mechanism there shown.

In the accompanying drawings Figure 1 is a front view of so much of a circular knitting machine as is necessary to an understanding of our invention; Fig. 2 is a plan view with the knitting head removed and parts shown in section; Fig. 3 is a detail view of the take-up mechanism and the measuring mechanism associated therewith; Fig. 4 is a face view of the main pattern mechanism; Fig. 5 is a detail view. Figs. 6 and 7 are detail views.

The invention is shown in connection with a machine of the rotary needle cylinder type, but it will be understood that we do not limit ourselves in this respect, as the broad features of our invention can be carried out in connection with machines of the rotary cam cylinder type.

In the drawings, 1 is the knitting head which may be for making rib or plain fabric.

2 is the fixed head base connected by standards or housings 3 supported on the fixed base ring 4. The revolving take-up ring 5 is supported in the fixed base ring 4 and it is rotated from the rotary needle cylinder as in common practice by the hangers 6. This take-up ring carries the take-up mechanism. This may be of any desired form, but in the particular construction we show this mechanism as embodying the essential features shown in Letters Patent of the United States granted to F. B. Wildman, 601,297, March 29, 1898, and G. L. Ballard, November 23, 1909, #940,656, involving a pair of take-up rollers 7, 8, between which the fabric is drawn. These rollers are geared together at 9 to rotate in unison. They are journaled in the hangers 6 and they bodily revolve with the take-up ring. The take-up roll 8 is driven by a worm wheel 10 thereon, with which meshes a worm 11. This worm is driven through a friction clutch like that shown in Fig. 4 of the Ballard patent mentioned, and which is indicated generally or in outline at 12. One member of this friction clutch is keyed to the vertical shaft 13 and is pressed down into frictional driving

contact with the other member for driving the worm 11 by a lever mechanism under spring tension, acting according to the demands of the fabric production to rotate said lower member to which the worm 11 is connected to rotate therewith. The shaft 13 is driven constantly through a gear 14 on its lower end meshing with a stationary rack 15 which is connected to the fixed base ring 4 by the hanger 16. This take-up mechanism is well understood by those skilled in the art and needs no further comment, the net result of the use of such take-up mechanism being that each rotation of the take-up rolls 15 represents a definite length of fabric which has passed between them. This being so, we drive our measuring member positively from the worm 11 which, of course, rotates uniformly with the take-up rollers and in a certain definite ratio in respect thereto. This measuring member may assume different forms, but in the particular construction shown it is in the form of a wheel 17 having ratchet teeth 18. It is mounted on a vertical stationary post 19 supported on the take-up ring 5. This measuring wheel is frictionally connected to a worm wheel 23 by a friction band brake 20 which is clamped by a screw 21 to the hub of the worm wheel 23 mounted to turn on the stationary post 19. The band is fiber lined, and has a pin 22 which extends up into the measuring wheel. The wheel 17, by reason of this friction connection, is turned when the worm wheel 23 is turned, and it is capable of being advanced or rotated independently of said worm wheel, the said friction band slipping in this action. The worm 23 is rotated in unison with and always in the same ratio to the worm 11 through a worm 24 on a shaft 25 journaled in a bracket 25^x fixed on the take-up ring, Fig. 1. This shaft carries another worm wheel 26 which is driven from the main worm 11 of the take-up mechanism. In addition to the slow measuring movement due to the friction drive just mentioned, the measuring wheel 17 is capable of being rotated step by step, one step for each revolution of the knitting head by a pawl 27 engaging its ratchet teeth 18. This pawl is carried by an arm 28 loosely mounted on the post 19. The arm has an extension or step portion 19^x provided with a set screw 29 to strike against the arm or extension 6^x of the hanger 5 or take-up standard 6 to limit the movement of the pawl arm in one direction, this movement being to restore the arm to normal position and being given by a spring 30, one end of which is attached to the arm and the other end being secured to a bracket 31 mounted fixedly on the post 19 and traveling with the take-up ring, this bracket being at all times in fixed relation to said ring.

The pawl arm 28 is moved to turn the ratchet by striking a cam 32 and riding

against the inner face thereof as the take-up ring and the mechanism carried thereby, including the said arm, revolves. This cam is fixed on the inner side of one of the stationary housings 3. When the pawl arm is moved by striking this cam, the pawl 27 will be given a throw to turn the measuring wheel, provided the said wheel is in position so that one of its teeth 18 is exposed to be engaged by said pawl. The measuring wheel, however, carries an adjustable measuring plate or block, or any desired number of these may be used. We show two in Fig. 2 at 33. These are fixed to the measuring wheel by screws 34 passing through slots 80 in the plates and into threaded openings 85 in the upper face of the measuring wheel, there being one of these openings for every ratchet tooth. The measuring plates shield the teeth against engagement therewith by the pawl 27 and more or less of the teeth may be shielded by using extension measuring plates as at 36. During the time the pawl is on the edge of one of these plates, as shown in Fig. 2, the throw of the pawl due to its carrying arm 28 striking the cam 32 will be without effect on the measuring wheel, which now will be performing its slow measuring movement through the described connections with the take-up rolls or rather with the take-up worm 11, and during this time the measuring of the pattern will be in accordance with the actual length of fabric passing through the take-up rolls. When, now, this slow measuring movement in accordance with the actual length of fabric has taken place and the pawl has dropped off of the measuring plate due to the said plate having passed the pawl and the pawl spring 37 exerting its force, the pawl will be in engagement with the end of the plate or with a tooth of the ratchet, and the next advance movement of the pawl arm by the cam 32 will give a quick step movement of the measuring wheel and this advancement of the measuring wheel will cause the cam cone or stud 39 on the measuring plate to come under and raise the pin 40 mounted in the bracket 31, and as this pin is connected through a rod 41 with a pin 42 slidably mounted in the post 19, said pin will be lifted also and elevate its arm 42^x into the path of a trip finger 43 which controls the main pattern mechanism, so that this will then be started to perform its cycle of operations. This main pattern mechanism is shown generally at A. It may assume various forms, but in the particular construction shown it includes a pattern wheel or wheels 44 four of these being shown fixed on a shaft 45 to which is fixed a pattern ratchet wheel 46. The shaft is journaled in a bracket 48^x fixed to one of the stationary housings 3. The pattern ratchet wheel 46 is operated by a pawl 47 when the latter is

free to engage therewith, said pawl being pivotally mounted on a slide 48 moving in bearings 49 fixed to said bracket. The slide is operated by an arm 50 at the upper end 5 of a rock shaft 51 journaled in the bracket 48^x and in the lower stationary bracket 52. The rock shaft is pressed by a spring 53 to retract the slide (*i. e.* to the right, Fig. 1), and it is operated in the other direction to 10 advance the slide and give the pawl its effective stroke by an arm 54 at the lower end of the rock shaft which is struck by a cam 55 supported by a post or posts 56 from the revolving take-up ring to revolve there- 15 with about the axis of the machine. This rock shaft is operated one or more times for each revolution of the machine, according to the number of cams 55 used, but though the pawl 47 will perform its stroke, it is not 20 always effective in turning the pattern ratchet. It is shown in Fig. 1 as rendered ineffective because it is resting upon a controller 57 consisting of an arm pivoted at 58 to the side of the bracket 48^x and held in 25 the position shown by a catch 59 engaging its inner end and maintaining its outer end raised with the pawl above the ratchet. The controller is raised to the position shown by a pin 69 on a controlling chain as herein- 30 after referred to.

The catch consists of an arm having an upturned end notched at 60 for receiving the inner end of the controller, said arm being fixed to the upper end of the rock shaft 61 35 journaled in bearings 62 fixed to the bracket 48^x, the said rock shaft being pressed by a spring 63 to hold the catch in operative position, *i. e.*, in holding engagement with the inner end of the controller. The trip finger 40 43 before mentioned is connected with the lower end of the rock shaft 61. Now, when through the slow measuring action of the measuring wheel 17 operating in a certain ratio to the fabric length passing the take-up 45 rolls, the pawl 27 is allowed to become effective in giving the measuring wheel its quick step movement, and the cam stud 39 has, as a result, lifted the arm 42 through the described connections, the trip finger 43 50 will be operated, and the catch 59 will be withdrawn, freeing the controller 57 which now falls at its free end and allows the pawl 47 to engage the pattern ratchet wheel. When the pattern ratchet is turned, the shaft 55 45 will be turned also, and the pattern wheels 44 will be rotated step by step, and as these pattern wheels carry pattern blocks 44^x to operate levers 63, 64, 65, 66, said levers will be operated. These levers are connected 60 in any suitable manner to various devices on the machine for controlling the pattern or character of the stitch. We have shown one of these connections at 64^x in part, and a connection at 65^x which latter will be referred to hereinafter, as an example of one

of the many functions of the machine which the pattern mechanism can be used to control. This particular connection will control yarn changers for striping as will be set forth later on. The connections leading 70 from some of the levers have been omitted, for instance, levers 63 and 66, to avoid complication in the drawing. Some or all of the levers may have arms 67 pressed upwardly by springs 68 to restore the levers 75 and the parts operated thereby to their normal positions after they have been operated by the blocks on the pattern wheels. The springs 68 may be seated in sockets of the bracket 48^x. 80

Associated with the main pattern drum made up of the before-mentioned wheels 44 on the shaft 45 is a controlling chain *a*. This chain is driven by a toothed chain wheel *a'* loose on the shaft 45 and driven by 85 the pawl 47 engaging teeth *a*² on said wheel. The chain thus can be driven independently of the pattern ratchet wheel 46. The chain is provided with links of three different heights, which exert control on the pawl 47. 90 The low links *b* allow the pawl to drop far enough to engage the ratchet 46 and turn the same when the pawl is freed from the controller 57 by the dropping of the latter as above described. The medium height 95 links *b'* are used to secure a dwell in the effective operation of the pawl because while these links are under the pawl it will not reach the teeth of the pattern ratchet 46 and hence the pawl will work idly so far as 100 the pattern drum 44, 44, is concerned. The pawl, however, will engage the teeth *a*² of the chain ratchet and the chain will thus be pawled around. When the pawl 47 falls all 105 the way down, it will move the pattern ratchet 46 by engaging its teeth and will also move the idler or chain ratchet *a'*, and it will continue to do this until a medium height link *b'* comes around, when the pawl will be 110 lifted to miss the teeth of the pattern ratchet but will still be in range of the idler ratchet teeth *a*². The lifting of the pawl by the medium height link will stop the pattern ratchet 46, but as just stated the chain ratchet will continue to move because its 115 teeth extend out beyond the edge of the medium high link. When a low link again comes beneath the pawl this will fall and engage the pattern ratchet to turn the same. These actions will continue until the pattern 120 drum has made a complete revolution, or such part of a full revolution as will complete one cycle of movement and the pattern has been completed. When a complete movement or cycle of the pattern ratchet has been 125 accomplished, the pin 69 on the chain *a* comes under the controller and lifts this, together with the pawl 47, the rear end of the controller 57 being thrown down into engagement with its catch 59 which holds 130

the controller in this position. The effect of this is to stop the ratchet 46 by lifting the pawl therefrom. The pawl, however, continues to act on the chain to pawl this 5 around by the pawl engaging the two teeth 70—71 formed on the chain itself. This action will carry the pin 69 on the chain from under the controller 57 which now will be maintained in its elevated position solely 10 by the catch 59, and will therefore be in condition to drop and restore the pawl into engagement with the ratchet as soon as the catch 59 is operated by the measuring mechanism, which it would not do had the pin 15 69 not been advanced from beneath the controller as just described. After the pawl has moved the chain by engaging with the teeth 70, 71, the movement of the chain ceases for as long as the pawl remains up. Further- 20 more, the pattern ratchet remains at rest for as long as the pawl is held up by the controller 57, or in other words, the whole main pattern mechanism A remains at rest, and during this time the measuring action 25 of the measuring wheel 17 goes on and at the prescribed time the controller will be released by the striking of the trip wire 43 by the arm 42 as already described, and the pawl 47 will then drop.

30 In order to insure that the pattern ratchet and chain be maintained in time with each other, we provide a long tooth X in the pattern ratchet, this being longer than the normal stroke of the pawl, and when 35 this comes under the pawl the pattern ratchet will stop, and it will remain in this position until a high link on the chain comes under and lifts the pawl which, in turn, lifts a stop finger 72 (which reciprocates with 40 the pawl) so that the rear end 72^x of this will be depressed below the level of the fixed stop 73 on the frame whereupon the pawl can perform a long stroke and thus engage the next tooth following the long tooth, and 45 then the movement of the ratchet will be resumed and this will take place at a definite fixed relation to the movement of the chain. By the use of the measuring wheel 17 the main pattern wheel is out of action until the 50 pattern is to be formed by said main pattern mechanism, and then it is thrown into action. By this a short chain may be used.

55 Reverting to the means for varying the length of stroke of the pawl 47 to secure the timing action between the pattern ratchet 46 and the controller chain a, the stop lever or finger 72 is mounted on the same pivot with the pawl 47, but is capable of having pivotal movement independently of said 60 pawl. This stop finger is under tension of a spring 74 which tends constantly to force its forward end downwardly. This forward end of the stop finger, as shown in Fig. 2, bears on a lateral extension 47^x of the pawl.

During the normal working of the pawl, 65 i. e., when it is engaging either the teeth of the pattern ratchet or the teeth of the chain ratchet a', the pawl is down, or part way down, and in either case the stop finger is in such position, being controlled by the position of the pawl, that its rear end is in line with the fixed stop stud 73 on the fixed bearing 49, so that as the pawl slide 48 retracts under the action of the spring 53 and the rock shaft 51, the end of the stop finger will 70 strike the said stop stud and the pawl 47 will be arrested or limited to its short stroke, it being understood that the pawl slide 48 on this stroke is driven by the spring 53, and therefore the slide can be arrested to 75 make the stroke a shorter one than the full stroke of which the spring is capable of imparting to the slide.

As above described, when a long tooth of the pattern ratchet such as shown at X 85 comes under the pawl, then so long as the short strokes of the pawl are maintained as just described by the stop finger 72, 72^x striking the stop stud 73, the pattern ratchet will remain at rest because the length of the 90 pawl's stroke is not far enough back to engage the next tooth. Now for starting the pattern ratchet it is necessary to give the pawl a long rearward stroke in order that it may engage the next tooth in the rear. 95 This is done by the high point 70 on the chain coming under the pawl and lifting it, and this action causes the lifting of the front end of the stop finger because of its engagement with the pawl at 47, thus throwing 100 its rear end below the level of the fixed stop so that the spring 53 and rock shaft 51 can move the slide 48, together with the pawl 47, far enough rearwardly to cause the pawl to engage the next tooth in the ratchet. 105

It will be seen from the above that the pattern ratchet and chain will be kept in time, because the starting of the ratchet, after the long tooth has come under the pawl, is dependent on the chain reaching a 110 certain predetermined relation thereto.

Now, regarding one example of the functions performed by the pattern mechanism, reference is made to the applications for Letters Patent of the United States of G. 115 L. Ballard, 840,378, filed May 22, 1914, or 851,152, filed July 15, 1914, in which yarn changer mechanism is controlled by star wheels as at 80 on the main frame operated by pins 81, 82, on the take-up ring. Of 120 these pins the one marked 81 is shiftable radially into and out of operative position in relation to the star wheels. These star wheels, as in the applications referred to, have wide and narrow teeth. The pin 81 is 125 shifted by a lever 83 having a pin 84 which strikes a cam 85 on the main frame. This cam is shifted vertically to be in line or in

the plane of movement either with the pin 84 or the pin 81, these pins being at different levels. When in line with the pin 81 this is moved inwardly to inoperative position, and misses the star wheels, and at the same time the other pin 84 is moved outwardly to be in line with the cam 85 when this is shifted vertically into the plane of movement of the said pin 84. When the pin 84 hits the cam, said pin is moved radially inward and the other pin 81 is moved outward so as to strike the narrow teeth of the star wheels. The cam 85 is moved vertically by a rod 65^a connected to the lever 65^x which, 15 as above described, is operated by the pattern drum.

We claim as our invention:

1. In combination in a circular knitting machine, a rotary needle cylinder, pattern mechanism including a measuring means traveling bodily with the needle cylinder, a part of said pattern mechanism being on the fixed frame and controlled from said traveling measuring means, that portion on 25 the main frame including a step by step pattern member, with means for operating the same from a part traveling in unison with the rotary needle cylinder, and connections leading to parts of the knitting machine 30 from said fixed frame pattern means to be controlled thereby.

2. In combination in a knitting machine having a rotary needle cylinder, pattern mechanism on the fixed frame, take-up 35 mechanism and measuring means traveling bodily with the rotary needle cylinder, said measuring means being operated in consonance with the length of fabric produced, and means operated by the said measuring 40 means for starting the fixed frame pattern mechanism, said fixed frame pattern mechanism throwing itself out of operation after it has performed a prescribed cycle of movement.

45 3. In combination in a circular knitting machine, a rotary needle cylinder, take-up mechanism traveling bodily with the rotary needle cylinder including take-up rolls with means for rotating them as they revolve 50 bodily with the machine, pattern mechanism in part supported on the fixed frame, said pattern mechanism including measuring means traveling bodily with the needle cylinder and take-up, said measuring means controlling the operation of the pattern mechanism on the fixed frame, and means for driving the measuring means from the take-up mechanism in consonance with the take-up movement of the take-up rolls, substantially as described.

60 4. In combination in a circular knitting machine, a rotary needle cylinder, pattern mechanism on the fixed frame and measuring means traveling with the needle cylinder

and rotated in consonance with the length of 65 fabric produced and controlling means for the pattern mechanism operated from said measuring means, substantially as described.

5. In combination in a circular knitting machine, a rotary needle cylinder, pattern 70 mechanism on the fixed frame, a controller for said pattern mechanism, a measuring member on the rotary part of the machine traveling bodily therewith, means for operating said measuring means in consonance 75 with the length of fabric produced, and trip mechanism for the controller on the fixed frame and operated by the said traveling measuring means to start the said pattern mechanism, substantially as described. 80

6. In combination in a circular knitting machine, a rotary needle cylinder, take-up mechanism revolving with the machine and including take-up rolls, means for rotating the take-up rolls, pattern mechanism on the 85 fixed frame, a measuring member rotating about a vertical axis, off to one side of but parallel to the axis of the machine, means for driving said measuring member in consonance with the take-up movement of the 90 take-up rolls, and connections operated by the traveling measuring member for controlling the fixed frame pattern mechanism, substantially as described.

7. In combination in a circular knitting machine, a rotary needle cylinder, a take-up mechanism revolving with the rotary needle cylinder and including take-up rolls, a measuring member, means for driving the same in consonance with the take-up rolls, 95 pattern mechanism on the fixed frame, a contact on the fixed frame controlling the pattern mechanism, and a contact traveling with the machine and shifted into and out of operative position, to hit or miss the 100 frame contact, by the measuring member, said measuring member consisting of a wheel turning about a vertical axis off to one side of and parallel with the machine's axis and said shifting contact moving vertically, substantially as described. 110

8. In combination in a circular knitting machine, a rotary needle cylinder, take-up rolls revolving bodily about the axis of the machine, means for rotating the take-up 115 rolls, a measuring wheel rotatable about a vertical axis and traveling bodily about the axis of the machine with the take-up, means for giving the measuring wheel a slow rotation in consonance with the rotation of the take-up rolls about their own axes, means for giving the measuring wheel a quick step by step movement, a pattern mechanism mounted on the fixed frame, contact means on the fixed frame controlling the pattern 120 mechanism and contact means traveling with the take-up and measuring wheel, and shifted by the said measuring wheel for hit- 125

ting or missing the contact first mentioned to thereby control the main pattern mechanism, substantially as described.

9. In combination in a circular knitting machine, a rotary needle cylinder, take-up rolls revolving bodily about the axis of the machine, means for rotating the take-up rolls, a measuring wheel rotatable about a vertical axis off to one side of and parallel with the machine's axis and traveling bodily about the axis of the machine with the take-up, means for giving the measuring wheel a slow rotation in consonance with the rotation of the take-up rolls about their own axes, means for giving the measuring wheel a quick step by step movement, a pattern mechanism mounted on the fixed frame, contact means on the fixed frame controlling the pattern mechanism and contact means traveling with the take-up and measuring wheel, and shifted by the said measuring wheel for hitting or missing the contact first mentioned to thereby control the main pattern mechanism, said shifting contact being movable vertically and said measuring wheel having a cam for lifting said contact, substantially as described.

10. In combination a rotary needle cylinder, a revolving take-up including take-up rolls, a worm rotating about a vertical axis for driving the same, a friction clutch for driving the worm, means for varying the pressure at the friction clutch according to the demands of the tension of the fabric, a measuring wheel, a vertical post traveling with the take-up and about which the measuring wheel turns, a friction drive connection between the said worm and the measuring wheel, a fixed frame contact and a contact traveling with the measuring wheel for operating the latter step by step by the striking of said contacts, a pattern mechanism on the fixed frame, and means for controlling the same from the measuring wheel, substantially as described.

11. In combination in a knitting machine, a rotary needle cylinder, take-up mechanism revolving bodily with the machine, a fixed rack on the machine, a gear connected with the take-up mechanism and engaging the rack to be operated thereby, measuring means revolving bodily about the axis of the machine with the take-up mechanism, a pattern mechanism on the fixed frame, a reciprocating pawl for operating the same, means for operating the pawl from a rotary part of the machine, a controller for the pawl on the fixed frame to maintain it out of operative relation to the pattern mechanism, means on the fixed frame for holding the controller in effective position, a contact traveling with the measuring means and shifted thereby, and a contact on the fixed frame to be struck by the shifting contact to

operate the controller, substantially as described.

12. In combination with a knitting machine, pattern mechanism comprising a pattern drum, a pattern ratchet wheel fixed to the said drum, a pawl engaging the pattern ratchet wheel, a controlling member moving about the axis of the drum and having controlling blocks of three different heights to act on the pawl, the lowest block allowing the pawl to engage the pattern ratchet and the medium height block holding the pawl from the pattern ratchet, a controller for the pawl, a pin on the controlling member for operating the controller to hold the pawl out of operation, the said pattern ratchet having an extra long tooth, means for limiting the stroke of the pawl to agree with the distance between the short teeth of the pattern ratchet wheel, said means being operated by the high blocks on the controlling member to allow the pawl to have a long stroke, and a latch for retaining the pawl controller and measuring means for controlling the latch, substantially as described.

13. In combination a pattern ratchet wheel, a reciprocating pawl to operate the same, a controller chain to act on the pawl to control its engagement with the pattern ratchet, said pattern ratchet having short teeth and a long tooth, means for stopping the pawl on its rearward stroke to make the length of stroke of said pawl agree with the short teeth, means on the controller chain for eliminating the stopping of the pawl to allow the same to perform a longer stroke to carry it beyond the limit of the long tooth, whereby the said pattern ratchet and controller chain are kept in time, said stop means consisting of a pivoted member moving with the pawl and a stop on the frame to engage said pivoted member, substantially as described.

14. In combination a pattern drum, a pattern ratchet thereon, a reciprocating pawl to engage the pattern ratchet, a pivotally mounted controller member for lifting the pawl from the ratchet, a catch for holding the controlling member with the pawl lifted, a controlling chain having a pin to engage the pivoted pawl controller, the said controlling chain having links of three different heights, the low links permitting the pawl to engage the teeth of the pattern ratchet, the intermediate height links preventing the pawl from engaging the pattern ratchet while allowing it to engage the chain ratchet, and the high links having teeth to be engaged by the pawl to carry the pin from under the pivoted pawl controller, the said pattern ratchet having a long tooth, means for driving the pawl positively forward, and a spring for returning the pawl for its rear stroke, variable stop means for

regulating the length of the rearward stroke of the pawl, the said stop means being controlled by the controlling chain so that the pawl will perform a short stroke to engage 5 the short teeth, and bring the controller chain and pattern ratchet in time when the long tooth comes beneath the pawl and the pawl will then perform a long stroke to

carry it over the long tooth and in position to engage the short teeth, substantially as 10 described.

FRANK B. WILDMAN.
